HYDRAULIC CONTROL FOR FINISHING
ROLLS OF TERNE PLATE RIGSElwin A. Matteson, Youngstown, Ohio, assignor
to The Aetna-Standard Engineering Company,
Youngstown, Ohio, a corporation of Ohio

Application August 6, 1949, Serial No. 109,026

7 Claims. (Cl. 118—114)

1

This invention relates to a coating rig and, more particularly, to a coating rig comprising a frame; a pot within the frame containing a coating liquid; means for guiding the material to be coated into, through and out of the pot; a coating roll assembly located in the pot above the level of the coating liquid; and, determining the spacing of the rolls in the coating roll assembly, a mechanico-hydraulic system mounted on the frame in juxtaposition to the coating roll assembly.

In a more specific aspect, the invention relates to a rig of this kind which may be used for applying a coating liquid to continuous or discontinuous lengths of strip material. The coating liquid contemplated in the preferred embodiment of the invention, described hereinafter, is molten metal; however, the coating liquid may if desired take the form of an organic material partaking for example of the nature of a resin, either maintained at a temperature above its melting point or in solution in a solvent. Where a molten metal is used, the latter may be a non-ferrous metal such as tin, lead or the like, in which case the rig may be used for galvanizing, terne plating or some similar operation. For convenience, the invention will be described hereinafter as used in a continuous process of manufacturing terne plate.

One of the major objects of the invention is to provide a rig of this kind lending itself to the production of uniformly coated strip material.

Other objects of the invention are, inter alia, to provide a coating rig in which the thickness of the coating may readily be varied by effecting suitable adjustments outside the rig itself and particularly outside the coating pot forming part of the rig; to provide a coating rig in which the spacing between co-acting rolls in the coating roll assembly may be equalized from end to end thereof by increasing or decreasing the forces operating on one end of the coating roll assembly while maintaining unchanged the forces acting on the other end of the coating roll assembly; and to provide a coating rig in which, once the adjustment required to give a desired thickness has been made by the operator, adjustment for wear in the coating roll assembly is made automatically in response to forces originating outside the coating roll assembly.

Another object of the invention is to provide a coating rig characterized by a strong, sturdy, yet simple coating roll assembly in which adjustments and compensation for wear are effected by means of a mechanico-hydraulic control system disposed largely in space in the rig, not otherwise used that is made available by forward inclination of the coating roll assembly and in

2

which one or more roll wiper assemblies can conveniently be incorporated in juxtaposition to the coating rolls themselves without interference with or from the mechanico-hydraulic control system.

Still another object of the invention is to provide a coating roll assembly incorporating a sub-frame supported from the main frame of the coating rig made up in part of two side pieces or panels having therein openings in which are received bearing block supports each of which in turn receives a plurality of bearing blocks mounting the necks of the coating rolls, such bearing blocks and bearing block supports being capable of relative movement to permit closer approach of the coating rolls as wear occurs, this notwithstanding use of bearing block supports and overlying cap members to journal certain elements of the gear train serving to transmit power to the individual rolls forming part of the coating roll assembly.

Other objects and advantages of the invention will be apparent from the accompanying drawings, in which Figure 1 is a vertical section, with parts in elevation, along the central longitudinal axis of the machine as a whole; Figure 2 is an end elevation on an enlarged scale of the coating rolls and associated parts, the coating pot appearing in section; Figure 3 is a corresponding transverse elevation, with parts in section, of the coating rolls and associated parts as seen from the right in Figure 1 but for convenience illustrated as if disposed vertically; Figure 4 is an enlarged end elevation of the roll drive system as it would be seen from line 4—4 of Figure 3; Figure 5 is a corresponding end elevation of the roll drive system as it would be seen from line 5—5 of Figure 3; Figure 6 is an elevation, with parts in section and other parts omitted entirely, of one of the two roll wiper assemblies, the same being illustrated as in Figure 3; Figure 7 is a vertical section with parts in elevation along line 7—7 of Figure 6, the section corresponding generally to that of Figure 2 but one of the panels being omitted to reveal details of the roll wiper assemblies; Figure 8 is a plan of the cylinder supporting means, hydraulic cylinders, and associated piping; and Figure 9 is a schematic representation of the hydraulic system.

Referring first to Figure 1, what is there shown is a metal frame 1, disposed largely below floor level, within which is a lining of insulating brick, the same being designated 2. Interiorly of brick lining 2 is the metal coating pot 3 which for the most part projects upward very slightly beyond the top of frame 1 but toward the right-hand end thereof has an upward extension 3a.

The latter is V-shaped as seen from above, conforming to the shape of the end of coating pot 3. Abutting the extension 3a and extending transversely across the coating pot 3 is a partition 4 which divides the coating pot into two parts, one of which contains the heating and charging elements and the other of which contains the coating roll assembly.

Underlying both parts is a coating metal pool 5, the same reaching to approximately the level of line L—L. Floating thereon but reaching within extension 3a a level approaching the top of partition 4 is a supernatant oil pool 6, the same consisting of palm oil, mineral oil, or a mixture of both. Within the part of the pot to the left of partition 4 as seen in Figure 1, the oil reaches a height of a few inches only; to the right of partition 4, it is of a depth sufficient to cover most or all of the coating roll assembly. The supernatant oil pool is commonly employed in this manner in coating rigs and for that reason further reference to it will not be made.

To the left of and above the level of the coating pot 3 are feed rolls 7a and 7b, the same constituting the means for guiding into the coating pot the material being coated, usually continuous strip material. At the opposite end of coating pot 3 are two pairs of catch rolls 8a and 8b, such rolls constituting the means for guiding out of the coating pot the material being coated. Between feed rolls 7a and 7b and catch rolls 8a and 8b the material being coated follows the path P, passing through an opening 9 in partition 4 in proceeding from the left-hand part to the right-hand part of coating pot 3.

In the part of coating pot 3 to the left of partition 4 are heating elements 11a, 11b, 11c, etc., the same taking the form of immersion heating elements of conventional type. They form no part of the present invention except insofar as they serve to keep the metal in coating pot 3 in liquid condition. Immediately to the left of partition 4 is charging apparatus 12, the same likewise being of a conventional type. Within the free area in coating pot 3; i. e., the area not occupied by heating elements 11a, 11b, 11c, etc., and the charging apparatus 12 are an upper guide assembly 13 and a lower guide assembly 14. Between them lies the path P of the material being coated.

Immediately to the right of partition 4 and in juxtaposition to opening 9 are an upper guide assembly 15 consisting of a series of parallel guide rods 15a held in place on an apron 15b and a lower guide assembly 16 likewise consisting of a series of parallel guide rods 16a held in place on an apron 16b. Upper and lower guide assemblies 15 and 16 serve to guide the material being coated to the lower or near end of the coating roll assembly 18. Together with guide assemblies 15 and 16, coating roll assembly 18 occupies most of the area of pot 3 to the right of partition 4 other than that taken up by the secondary heating element 17.

Associated with coating roll assembly 18 is a mechanico-hydraulic control system, generally designated 19, to be described hereinafter.

As seen in Figures 2, 3 and 7, the coating roll assembly is mounted between two side pieces or panels 21 and 22, the former being the panel on the near side and the latter panel on the far side of the apparatus shown in Figure 1. The two side panels are characterized by forwardly extending portions 21a, 22a, and rearwardly extending portions 21b, 22b, the same constituting the means whereby the two side panels 21 and 22

are mounted in the apparatus. In the case of rearwardly extending portions 21b and 22b, the latter also serve as means from which parts of the mechanico-hydraulic system 19 are supported.

To that end, side panels 21 and 22 are located on the one side on brackets 23, 23', extensions 21a, 22a thereof being adjustably positioned on the brackets by means of adjusting screws 24, 24', and, on the other, by means of adjusting screws 10 25, 25', bearing against the top of partition 4. Adjusting screws 24, 24' and 25, 25', along with other adjusting screws suitably located relative to side panels 21 and 22, serve to position the side panels in lateral alignment with each other and 15 in proper relation to the rest of the installation.

As shown in Figure 2, side panel 21, to which side panel 22 is similar in substantially all respects, is generally U-shaped, the bight therein taking the form of a generally rectangular opening 26, extending from the upper part of the panel to a point at approximately the level of the line L—L marking the top of the molten metal in pool 5. Adjoining rectangular opening 26 on the left-hand side thereof as seen in Figure 25 26 are three lesser openings 27, 28 and 29, the purpose of which will appear hereinafter. Rectangular opening 26 is so located that its long sides define an angle of roughly 15° to the vertical; by the same token, its short sides define an angle 30 of roughly 15° to the horizontal. In consequence, the coating rolls mounted in rectangular opening 26 inclined forward in the apparatus as indicated in Figures 1, 2 and 7.

Extending between side panels 21 and 22 are 35 the coating rolls, arranged in pairs. There may be one pair or more than one pair, as desired, although in the preferred embodiment of the invention, shown in the drawings, three stacked pairs are utilized. The forward or anterior roll 40 in the bottom pair is designated 31; the rear or posterior roll, 32. The anterior roll in the middle pair is designated 51; the posterior roll, 52. In the top pair, the anterior and posterior rolls are designated 61 and 62, respectively.

45 Referring to Figure 3 and for the moment to anterior roll 31, the same is provided at the left-hand side thereof with a cylindrical neck 33 adapted to rotate within roller bearings 34. The latter are held in place in a bearing block 35 the 50 interior of which has the shape of a hollow cylinder and the exterior of which takes the form of a cube or other rectangular parallelepiped. Bearing block 35, which thus serves as the supporting means for neck 33 of anterior roll 31, is 55 characterized also by upper and lower peripheral flanges, shown in dotted lines in Figure 2, which are located at the base of the bearing block in proximity to the adjacent end face of anterior roll 31. Accommodating the body but not the 60 flange at the bottom of bearing block 35 is a bearing block support 36, shown to best advantage in Figure 2, which as seen in end elevation is roughly channel-shaped. Bearing block 35 fits into the right-hand end of channel 37 in 65 bearing block support 36 with its lower flange abutting the inside face of the bearing block support. The latter in turn fits snugly into the rectangular opening 26 in side panel 21 with its two lateral flanges 36a and 36b, shown in dotted 70 lines in Figure 2, abutting the inside face of the panel.

A like bearing block support, facing in the opposite direction, is similarly located in the rectangular opening in side panel 22.

75 The channel 37 in bearing block support 36

and the like channel in the bearing block support in side panel 22 are largely, but not entirely, occupied by bearing blocks supporting the necks of anterior roll 31 and the two like bearing blocks, one at each end, supporting the necks of posterior roll 32. As indicated in Figure 2, the bearing blocks at the same end of the coating roll assembly are so proportioned that part of the original channel in the bearing block support remains open at the center as shown in Figure 2. Thus, there is considerable clearance between them, but not between the rolls themselves, after the bearing blocks are positioned in their respective bearing block supports. The bearing blocks supporting anterior roll 31 tend to slide toward the anterior ends of the channels in the bearing block supports by virtue of the above-described inclination of the coating roll assembly; similarly, the posterior bearing blocks need not and ordinarily will not fit snugly against the adjoining upright side of the bearing block support, being urged by gravity and otherwise toward a position in which posterior roll 32 would be in contact, but for the presence of the material being coated, with anterior roll 31.

In the lower left-hand corner thereof as seen in Figure 2, bearing block support 35 is slotted to provide an end opening 38 spanned by a pivot pin 39 on which, within opening 38, is mounted a bell-crank lever 41. The latter is provided with an inboard arm 42 bearing against the proximate side of the bearing block mounting posterior roll 32 and an outboard arm 43 characterized by a lateral off-set 43a by which bell-crank lever 42 is caused to project out of the plane of side panel 21 to an extent sufficient to enable the end of outboard arm 43 to clear the outside face of the panel. At the outer end of outboard arm 43 is a yoke 44 pivoted to an upwardly directed connecting rod 45.

The arrangement just described, which is that characterizing the near end of the bottom pair of rolls as seen in Figure 2, is substantially duplicated at the opposite ends of rolls 31 and 32. However, referring to anterior roll 31 as seen in Figure 3, the latter has at the far end thereof a roll neck 46 provided with a roll neck extension 47 carrying a gear 48 held thereto by a key and key-way 49. Roll 32, the posterior roll of the bottom roll pair, is likewise provided with a roll neck extension and a gear keyed thereto. These gears, which form part of the power train, do not mesh with each other but instead mesh with two idlers which will be described hereinafter.

Referring again to Figure 2, the middle row of rolls is made up of anterior roll 51 and posterior roll 52. The rolls are supported as shown in two like bearing blocks which are generally similar to bearing block 35, such bearing blocks being themselves positioned in bearing block support 53. The latter is generally similar to bearing block support 36, which underlies it, being provided with an end opening in which is pivotally mounted a bell-crank lever 54 similar to bell-crank lever 41. However, bell-crank lever 54 has a lateral off-set 54a which extends oppositely to off-set 43a of bell-crank lever 41. This state of affairs causes the outboard arm of bell-crank lever 54 to project not in the same direction as the outboard arm of bell-crank lever 41 but in the opposite direction relative to side panel 21. As a result, the end of the outboard arm of bell-crank lever 54, and therefore connecting rod 55, is positioned on the far side of side panel 21, as indicated by dotted lines in Figure 2.

In these and other respects, bearing block

support 53 at the near end of the coating roll assembly serves the same function as bearing block support 36; however, it is not so shallow, being of the somewhat greater depth indicated in Figure 2. The opposite bearing block support, correspondingly located in side panel 22, is of the same dimensions as bearing block support 53. It is similar thereto in all respects except that toward the bottom thereof it is provided with two cognate transversely extending circular openings receiving two stationary pins on which are rotatably mounted the two idlers previously mentioned.

Figure 3 shows a stationary pin 57 carrying an idler 58 meshing with the gear 48 on the roll neck extension 47 forming part of roll 31 of the bottom roll pair. A collar 59 serves to retain idler 58 in place on stationary pin 57. Back of it is a similar pin, paralleling pin 57, carrying an idler meshing with the gear mounted on the roll neck extension forming part of posterior roll 32 of the bottom roll pair. Each idler meshes not only with the gear therebelow but also with a like gear thereabove mounted on the roll neck extension of one of the rolls of the middle roll pair, gear 60 on the roll neck extension of anterior roll 51 appearing in Figure 3. The relationship between the gears is illustrated in Figure 4.

The rolls of the top roll pair comprise anterior roll 61 and posterior roll 62, the same being carried in bearing blocks and bearing block supports similar to those used with the rolls of the middle roll pair. Bearing block support 63 carrying the bearing blocks at the near end of the rolls of the upper roll pair is shown in Figure 2, the same being similar to and of substantially the same dimensions as bearing block support 53. Bearing block support 63 is slotted at the end thereof and equipped with a bell-crank lever 64 characterized by a lateral off-set 64a. The latter serves to project the outboard end of bell-crank lever 64 outwardly of side panel 21 as shown in Figure 2, so that connecting rod 65, which is pivoted to bell-crank lever 64, appears in full lines in Figure 2.

At the opposite ends thereof, the rolls of the top roll pair are constructed and supported similarly to the rolls of the middle roll pair; that is to say, a bearing block support is provided which is equipped with circular openings carrying stationary pins mounting idlers which are held in place by collars, just as in the case of the pins, idlers and collars underlying them on the same side of the roll assembly. Figure 3 indicates the manner in which idler 66 is rotatably carried by a stationary pin 67, being retained in place thereon by the collar 68. Idler 66 meshes the gear 60 therebelow and with a gear 69 thereabove, the latter being mounted on the roll neck extension forming part of anterior roll 61 on the top roll pair. Posterior roll 62 is similarly constructed, equipped and arranged. Reference is made to the showing in Figure 4, from which it appears how the gears at the ends of the rolls of the top roll pair mesh with the idlers immediately below them.

Attention is particularly called to the fact that unlike the idlers between anterior rolls in the coating roll assembly, the axes of which are aligned with the axes of the anterior rolls as indicated by line A—A in Figure 4, the idlers between posterior rolls are mounted forward of the plane, represented by the line B—B, of the axes of the posterior rolls themselves, this to per-

mit continued intermeshing of the idlers and gears notwithstanding wear on and resulting forward movement of the posterior rolls under the influence of the mechano-hydraulic control system hereinafter described.

At the opposite ends thereof, anterior and posterior rolls 61 and 62 differ from the corresponding ends of the rolls of the middle and bottom roll pairs in that they are provided with roll neck extensions on which are fixedly mounted gears meshing with two mutually intermeshing idlers one of which meshes with a driving pinion. As appears from Figures 3 and 5, the gears at this end of rolls 61 and 62 are designated 71 and 72; respectively, they mesh with idlers 73 and 74 mounted on stub shafts 75 and 76. Idlers 73 and 74 intermesh with each other and one of them, idler 73, meshes with the pinion 79 on drive shaft 80. Stub shafts 75 and 76 are journaled at their inboard ends in a cap member 77 overlying bearing block support 63. Cap member 77 fits into a correspondingly shaped recess in side panel 21, to which it is bolted as shown in Figure 2. Formed integrally with but off-set laterally from cap member 77 is a guard 77a, shown in end elevation in Figure 3. As appears from Figure 3, stub shafts 75 and 76 are journaled at their outboard ends in guard member 77a.

At the opposite side of the coating roll assembly, the several bearing block supports are surmounted by a cap member 78 which is similar to cap member 77 but lacks a guard similar to guard 77a and therefore is flush with the outer face of side panel 22.

Tracing the power train from drive shaft 80, the latter rotates pinion 79, which in turn serves to rotate idler 73 on stub shaft 75. Intermeshing idler 74 on stub shaft 76 rotates at the same time, but necessarily in the opposite direction. Idlers 73 and 74 respectively rotate gears 71 and 72 mounted on the roll neck extensions forming part of rolls 61 and 62, this being by virtue of the relationship illustrated in Figure 5. Power so communicated to rolls 61 and 62 is transmitted therethrough to the opposite ends thereof as seen in Figure 3, where gear 69 at the end of anterior roll 61 and the like gear at the corresponding end of posterior roll 62 mesh with and rotate the idlers immediately therebelow, which in turn mesh with and rotate the gears on rolls 51 and 52. Rotation of these gears serves, through the intervention of the idlers immediately therebelow, to rotate the gears at the corresponding ends of rolls 31 and 32.

Thus the individual rolls in each of the three pairs of coating rolls are rotated positively and simultaneously, but in opposite directions, in a manner such as to impart an upward movement to the material passing therebetween, all as indicated in Figure 4.

On cap member 78 are two flanges 85 and 86 which project inwardly of side panel 22, the same appearing in Figure 7. On opposite cap member 77 are two similar flanges projecting inwardly of side panel 21 one of which, 87, appears in Figures 3 and 6 along with flange 85, on cap member 78. In substantial alignment with these flanges are brackets disposed below the lower ends of the rectangular openings in side panels 21 and 22. Such brackets are shown, for example, in Figure 7, wherein appear the two brackets 88 and 89 affixed to the inside face of side panel 22. On the inside face of side panel 21 are two counterpart brackets one of which, 90, appears in the lower left-hand corner of Figure 6 opposite

bracket 88 on side panel 22. Thus on each of side panels 21 and 22 are two flanges and two brackets, the flanges overlying the brackets in the manner and to the extent shown in Figures 6 and 7. These flanges and brackets serve to support two roll wiper assemblies, one located anteriorly and the other posteriorly of the coating roll stacks.

Extending parallel to the coating rolls between the anterior flanges 85 and 87 on cap members 78 and 77, respectively, and between the corresponding posterior flanges on the same cap members; i. e., the flanges on the opposite sides of the rectangular openings in side panels 21 and 22, are two cross pieces taking the form of angle irons the ends of which are rigidly fastened, as by bolts, to the respective flanges. One of these, cross member 91, appears in elevation in Figure 6, while both of them, 91 and 92, appear in section in Figure 7. Connected thereto as herein-after described and located opposite the rolls of the middle roll pair are two other cross pieces, taking the form of modified angle irons, designated 93 and 94, the former appearing in Figure 6 and both appearing in Figure 7. Connected to cross pieces 91, 93 and 92, 94 and located below the rolls of the bottom roll pair immediately above brackets 88, 89, 90, etc., are two other cross pieces, designated 95 and 96, the former of which appears in elevation in Figure 6 and both of which appear in Figure 7 in the form of sections of angle irons. These various cross pieces form parts of the wiper blade frames, of which there is one for each roll wiper assembly.

As indicated in Figure 6, the wiper blade frame on the forward side of the coating roll assembly includes, along with cross pieces 91, 93 and 95, six upright members 97, 98, 99, 100, 101 and 102, these members likewise taking the form of angle irons. Six similar upright members form part of the wiper blade frame on the rearward side of the coating roll assembly, one of them, 103, appearing in Figure 7. To accommodate the several upright members, with which cross pieces 93 and 94 would otherwise interfere, the latter are cutaway as necessary. The various cross pieces and upright members are welded together to form roll wiper frames as generally indicated in Figure 6.

Welded to the wiper blade frames at their bases and cooperating with suitable holes in brackets 88, 89, 90, etc., are four pegs 104, 105, 106, etc., pegs 104 and 106 being shown in Figure 6 and peg 105 appearing in Figure 7. Both frames are principally supported from side panels 21 and 22 by being bolted at their tops to flanges 85, 86 and 87, etc., being held in position against lateral displacement by insertion of the pegs in brackets 88, 89, 90, etc. At the upper ends of the respective upright members are reinforcements 107, 108, 109, 110, 111 and 112, the same taking the form of square plates welded to the ends of the angle irons which form the respective upright members. A like reinforcement 113, one of six on the wiper blade frame not appearing in Figure 6, is shown in Figure 7. Bolts 114, 115 and 116, the latter being one of a pair at opposite ends of the coating roll assembly, appear in Figures 6 and 7.

Surmounting and bolted to reinforcements 107 and 108 is an oblong plate 120 which has counterpart parts in a plate 121 bolted to reinforcements 109 and 110, and a plate 122 bolted to reinforcements 111 and 112. A similar plate 123 mounting reinforcement 113 appears in Figure 7.

These plates serve as spring seats and guides for the spring assemblies and wiper rods to be described. For each such plate there are three wiper rods, one short one, one of intermediate length and one long one, each passing through a hole in the plate and surrounded above the plate by a compression spring.

The short rods on the forward wiper blade frame, seen in Figure 6, are designated 125, 126 and 127. Each is provided at its lower end with a bracket and a channel-shaped retainer for the soap stone wiper blade 129 shown in section in Figure 7. The short rod at the end of the rearward wiper blade frame appears in Figure 7, wherein it is designated 128. The channel-shaped retainer on the short rods of the rearward wiper blade frame is shown in section in Figure 7 as supporting soap stone wiper blade 130. At the opposite end of rods 125, 126 and 127 are spring assemblies 131, 132 and 133, the same comprising compression springs and spring retainers surrounded by nuts cooperating with appropriately threaded portions of the rods. A like spring assembly 134 appears in Figure 7 at the upper end of short rod 128.

As appears from Figure 6, three rods of intermediate length designated 135, 136 and 137 depend from spring assemblies overlying plates 120, 121 and 122, respectively. Three similar rods of intermediate length are mounted on the wiper blade frame on the rearward side of the coating roll assembly. The latter do not appear in Figure 6; however, one of these rods, designated 138, appears in part in Figure 7. Supported by rods 135, 136 and 137 just below the middle of the wiper blade frame shown in Figure 6 is the roll wiper blade 139, the same being held in place by a channel-shaped retainer mounted in brackets affixed, as by welding, to rods 135, 136 and 137. A like roll wiper blade 140 is similarly attached to the rods of intermediate length forming part of the wiper blade frame shown in end elevation toward the left-hand side of Figure 7, where such roll wiper blade is designated 140. Overlying rods 120, 121 and 122 as shown in Figure 6 are spring assemblies 141, 142 and 143, including nuts, spacers, and spring retainers.

The opposite wiper blade frame likewise includes three spring assemblies, one of which is shown in part in Figure 7. Mounted parallel to short rods 125, 126 and 127 and intermediate rods 135, 136 and 137 are three long rods, 145, 146 and 147, such rods being located as shown in Figure 6 in the wiper blade frame on the forward side of the coating roll assembly. Long rods 145, 146 and 147, by means of brackets and channel-shaped retainers, carry a soapstone wiper blade 149. Three like rods in the wiper blade frame on the opposite side of the coating roll assembly, one of which, 148, appears in Figure 7, carry a similar blade 150. The spring assemblies overlying long rods 145, 146 and 147 are designated 151, 152 and 153, respectively. The spring assemblies overlying long rod 148 does not appear in the drawings being concealed from view in each of Figures 6 and 7.

The three rods of intermediate length and the three long rods in each roll wiper assembly of necessity pass through openings in cross member 93 or 94, as the case may be, while the short rods are extended downward below the wiper blades to permit them also to pass through and thus be guided by cross members 93 and 94.

In a roll wiper assembly so constructed, an upward pressure is constantly exerted by wiper

blades 129 and 130 against the lower sides of the rolls of the top roll pair. Similarly, an upward pressure is constantly exerted by wiper blades 139 and 140 against the lower sides of the rolls of the middle pair. Wiper blades 149 and 150 maintain an upward pressure against the rolls of the bottom roll pair. Thus regardless of minor variations in the relative positions of the rolls making up a given roll pair, the wiper blades serve to move excess coating metal therefrom.

A mechanico-hydraulic system for determining the relationship to each other of the rolls of each roll pair is located in the space immediately behind the coating roll assembly, more particularly 15 the space which results from inclining the coating roll assembly forward as above described; i. e., at an angle of approximately 15° from the vertical. Such mechanico-hydraulic system includes a box-like frame 160, open at its ends, 20 which is mounted on extensions 21b and 22b of side panels 21 and 22, respectively. Three hydraulic cylinders designated 161, 162 and 163 are located at the end of frame 160 overlying side panel 21; similarly, three hydraulic cylinders 25 designated 164, 165 and 166 are located at the end of frame 160 overlying side panel 22. Looking axially of the machine as a whole, cylinders 161 and 162 are in alignment, so that the former does not appear in Figure 3; similarly, cylinders 30 164 and 165 are in alignment, so that cylinder 164 does not appear.

As indicated in Figure 8, cylinder 163 is off-set laterally from cylinders 161 and 162, being located on the opposite side of side panel 21; cylinder 166 is likewise off-set laterally from cylinders 164 and 165 being located on the opposite side of side panel 22. Thus cylinders 161, 162, 164 and 165, together with their respective piston rods, lie outside side panels 21 and 22; that is to say, on the sides away from the coating roll assembly. Cylinders 163 and 166, on the other hand, lie inwardly of side panels 21 and 22, as do also the piston rods associated with them.

The piston rods depending from cylinders 161 and 162 are linked to connecting rods 45 and 66, respectively, which, as has previously been pointed out, are located on the same side of side panel 21 by virtue of the fact that bell-crank levers 41 and 64 are characterized by off-set portions which require their outboard arms to project outward through the openings in side panel 21 designated 27 and 29, respectively. Thus connecting rods 45 and 66 appear in solid lines in Figure 2, while connecting rod 55, which is linked 45 at one end to the piston rod depending from cylinder 163 and at its other end to the outboard arm of bell-crank lever 54, is seen in solid lines through opening 28 and elsewhere is represented by dotted lines. A like state of affairs obtains 55 at the opposite end of the mechanico-hydraulic system, seen in Figure 7, where the connecting rod serving the bell-crank lever associated with opening 28 appears in solid lines as connected to cylinder 166, while the connecting rods serving the bell-crank levers associated with openings 27' and 29' appear largely in dotted lines.

As indicated in Figure 3, the two groups of cylinders overlying side panels 21 and 22, respectively, are served by pipes coupled to the cylinders above and below the pistons (not shown). Normally, pressure fluid such as oil is admitted to the space below the piston and withdrawn from the space above the piston in each cylinder, thus forcing the respective piston rods, connecting rods 70 and outboard ends of the several bell-crank

11

levers to their elevated positions. This results in the application of force by the inboard ends of the bell-crank levers, acting through the end openings in the bearing block supports with which they are associated, to the posterior bearing blocks, roll necks and rolls, thus urging them toward their anterior counterparts. The pipes passing the pressure fluid to and from the two groups of cylinders are supported by pipe supports 167 and 168, shown in Figure 3. Although for convenience indicated as broken away, the pipes are connected at their ends to four-way valves, so that, if desired, pressure fluid may be admitted to the space above the piston and withdrawn from the space below the piston in each cylinder, as may be desired at times. The arrangement as seen in plan is shown in Figure 8.

Figure 9 shows schematically the relation to the other parts of the hydraulic system of cylinders 164, 165 and 166, on one hand, and cylinders 161, 162 and 163, on the other. The two four-way valves are designated 169 and 170, respectively. The pipes leading from them are served by pressure-reducing valves 171 and 172, the purpose of which is to keep a predetermined uniform pressure on the pressure fluid admitted to the group of cylinders. Such pressure may, however, be varied so as to supply to the cylinders of one group fluid at a higher or lower pressure than that supplied to the cylinders of the other group, as may be necessary to adjust for inequalities inadvertently introduced in the assembly of the rolls or as a result of uneven wear on the roll necks. As indicated toward the bottom of Figure 9, the motor driven pump 173 is coupled to an accumulator 174 and a pressure switch 175, the latter forming part of the system for supplying the pressure fluid to the two groups of cylinders.

In practice, the use of fluid pressure motors in this manner has the important advantage that the force applied by the bell-crank levers to the bearing blocks remains substantially uniform notwithstanding wear in the rolls and roll necks.

If, for example, a system of adjustable springs were to be employed for the purpose of urging the rolls of the respective roll pairs toward each other, the pressure imposed by the springs would vary in proportion as wear changed the relationship of the rolls in the roll pairs; furthermore, since such springs would necessarily be located below the level of the oil in oil pool 6, it would at best be difficult to adjust the springs, and, when adjusted, the adjustment would represent nothing more than a guess as to the extent of the adjustment required to compensate for wear. On the other hand, by incorporating in a coating rig the mechanico-hydraulic system of the present invention, adjustment can be effected automatically without the need for intervention by the operator, whose services are required only at the start of the operation for the purpose of balancing the ends of the roll assembly against each other; however, if manual adjustment is indicated, as, for example, for the purpose of changing the thickness of the coating, such can be effected by suitably adjusting the setting of the pressure-reducing valves.

It is intended that the patent shall cover, by suitable expression in the appended claims, whatever features of patentable novelty reside in the invention.

I claim:

1. In a coating rig, a pot containing a coating liquid; a partition extending transversely of the

12

pot from one side of the pot to the other; two side panels within the pot extending forwardly from the partition, one on one side of the pot and the other on the opposite side of the pot; a roll assembly between said side panels through which roll assembly the material being coated travels on its way out of the pot; and, urging the rolls in the roll assembly toward each other, a fluid-pressure motor mechanically linked to at least one of the rolls in the roll assembly, said fluid-pressure motor and the parts linking it to the roll being located between the two side panels in the space between the partition and the roll assembly.

2. A coating rig of the kind defined in claim 1 in which the roll assembly is inclined forwardly.

3. A coating rig of the kind defined in claim 2 in which the roll assembly is inclined at an angle of about 15° to the vertical.

4. In a coating rig, an assembly comprising a sub-frame; a plurality of superimposed pairs of adjustably spaced rolls mounted in the sub-frame, said pairs of rolls being arranged to form a forwardly inclined roll assembly through which material being coated travels in an upward path but at an angle to the vertical; a hydraulic system supported from the sub-frame on opposite sides thereof but spaced rearwardly of the zone of discharge of material passing through the rolls, said hydraulic system including a plurality of fluid-pressure motors; and, at opposite ends of the rolls, a plurality of bell-crank levers coupled by connecting rods to the fluid-pressure motors, said bell-crank levers and connecting rods being located in the space defined by the zone of discharge of material passing through the rolls and those parts of the sub-frame from which the hydraulic system is supported.

5. In a coating rig, an assembly comprising a plurality of panels mounted in parallelism to each other, said panels having registering openings therein; a plurality of rolls extending therebetween with the necks of the rolls received within the openings in the panels; caps on the panels overlying the necks of the rolls; wiper frames located in juxtaposition to the rolls with their opposite ends attached to the caps on the panels; a plurality of spring-pressed wiper blades on the wiper frames bearing against the rolls; and, mounted on the panels, a plurality of fluid-pressure motors for determining the relative positions of the rolls, said fluid-pressure motors being mechanically linked to the necks of the rolls.

6. An assembly as in claim 5 in which the caps are provided with inwardly projecting flanges to which are attached the tops of the wiper frames.

7. An assembly as in claim 6 in which the panels are provided with inwardly extending brackets to which are attached the bottoms of the wiper frames.

ELWIN A. MATTESON.
